UNITED STATES PATENT OFFICE.

WILLIAM H. MOONEY, OF DAYTON, OHIO, ASSIGNOR TO THE DAYTON ENGINEERING LABORATORIES COMPANY, A CORPORATION OF OHIO.

CONTROLLING DEVICE FOR ELECTRICAL SYSTEMS.

1,401,352.

Specification of Letters Patent. Patented Dec. 27, 1921.

Application filed February 21, 1919. Serial No. 278,391.

To all whom it may concern:

Be it known that I, WILLIAM H. MOONEY, a citizen of the United States of America, residing at Dayton, county of Montgomery, 5 State of Ohio, have invented certain new and useful Improvements in Controlling Devices for Electrical Systems, of which the following is a full, clear, and exact description.

10 This invention relates to electric systems for an internal-combustion or explosion engine, including a motor for starting the engine, devices for supplying ignition to the engine and a source of current such as a 15 storage battery.

An object of the invention is to prevent waste of current of the battery. To accomplish this object I have provided manually controlled means for connecting the ignition 20 devices and battery and other manually controlled means for connecting the battery with the starting motor, said motor controlling means being ineffective unless the ignition devices are connected with the battery 25 by said first named means.

Other and further objects and advantages of the present invention will be apparent from the following description, reference being had to the accompanying drawing, 30 wherein a preferred embodiment of the present invention is clearly shown.

In the drawing is shown a wiring diagram which includes the features of the present invention.

35 In the drawing an internal combustion engine 20 is provided with a starting motor 21 which may be connected with the engine for starting purposes in any suitable manner. The drawing shows a pinion 22 having a 40 slideable driving connection with the motor shaft 23. Pinion 22 is moved by suitable mechanism not shown, into engagement with the flywheel gear 24.

A storage battery or other source of current 45 which is grounded at 26 is connected by means of a wire 27 with a switch element 29 of a relay switch 28. A relay magnet winding 30 is adapted when energized to cause the attraction of an armature 31 toward a 50 core 32 and thereby effect the movement of the switch element 29 toward a co-operating switch element 33. Switch element 33 is

connected by wire 34 with the starting motor 21 and the motor circuit is completed through a ground connection 35.

55

Current from the battery may be permitted to pass, when desired, through an ammeter 40, wire 41 to a switch contact 42 mounted on a support 43 of insulating material. A movable switch contact 44 is mounted 60 upon a shaft 45 but insulated therefrom, and said shaft 45 is adapted to be turned by the lever 46. This switch element 44 is yieldingly maintained in the "off" position as shown in the drawing by means 65 of a spring 47 having a portion thereof engaging a detent 48 formed upon the element 44.

When the lever 46 is turned counter clockwise until second detent 49 is engaged by the spring 47, a segmental portion 50 provided on the said element 44 will move into engagement with the switch element 42 and connect the same with a switch element 51. This motion of the lever 46 will also bring another segmental portion 52 of the element 75 44 into engagement with a switch contact 53. When this occurs current will flow through the battery through ammeter 40, wire 41, contact 42, switch element 44, contact 51, wire 54, switch terminal 55, wire 56 80 to the primary winding, not shown, of ignition coil 57. The other end of the primary wire of ignition coil 57 is connected by wire 58 with an ignition timer 59 having a ground connection 60, whereby, when the 85 contacts of the timer are closed, the primary ignition circuit will be completed. The high tension terminal of the ignition coil 57 is connected by means of a wire 61 with an ignition distributor 62 which is controlled in conjunction with the timer 59 and has terminals each connected with a spark plug in each of the engine cylinders, so that the ignition system just described will furnish complete ignition 90 for the engine. A second primary ignition circuit includes battery 25, ammeter 40, wire 41, switch contact 42, switch member 44, contact 53, wire 63, primary winding, not shown, of ignition coil 64, wire 65, ignition timer 66, also connected with the ground 100 connection 60. The high tension winding of the ignition coil 64 is connected by wire 67 with the ignition distributor 68 which operates in conjunction with the timer 66

and has its terminals connected with spark plugs in each of the engine cylinders. It will be seen that this second ignition system just described will also furnish complete ignition for the engine.

Condensers 69 and 70 are connected in shunt with timers 59 and 66, respectively, in order to reduce sparking at the timer contacts.

10 The ignition timer and distributor elements just described are preferably included in a single ignition unit, and said elements are all operated by common driving connection with the engine. Such an ignition unit is described and claimed in my Patent No. 1,348,368, issued August 3, 1920, and further description thereof is considered unnecessary as the specific construction of this ignition unit does not form a part of the 15 present invention.

The switch element 44 is provided with a third detent 71 which, if the switch lever 46 is turned still farther in a counter clockwise direction, will come into engagement 25 with the spring 47. With switch element 44 in this position the segment 52 will be moved out of engagement with the switch contact 53 while the segment 50 will still be in engagement with the switch contacts 51 30 and 42. Thus it will be seen that the battery will not be connected with the ignition coil 64 and ignition timer 66. The engine will be supplied with ignition through the agency of one of the ignition systems.

35 This arrangement may be found desirable where it is desired to hold one of the other ignition systems in reserve in case of emergency and to economize the battery current.

The switch terminal 55 is connected by 40 wire 72 with a switch contact 73 which is adapted to be engaged by a movable contact 74 actuated by a button 75. Contact 74 is connected by wire 76 with the relay winding 30 having a ground connection 77.

45 Whenever the switch element 44 connects one or both of the ignition systems with the battery, by depressing button 75, current may be sent from the battery to the relay winding 30. The relay energizing circuit 50 includes battery 25, ammeter 40, wire 41, contact 42, switch element 44, contact 51, wire 54, terminal 55, wire 72, contacts 73 and 74, wire 76, winding 30 and ground connections 77 and 26 to the battery 25.

55 It is apparent from the foregoing description that the present system prevents waste of battery current, due to an attempt to start the engine without the ignition system being connected to the battery. Before the 60 relay winding 30 can be energized to effect the closing of the motor circuit the ignition switch lever 46 must be turned to one of its on positions and in which one or both of the ignition timers will be placed in condition for effective operation by the engine.

If the lever 46 is in the off position as shown in the drawing, the contacts 42 and 51 will not be bridged by the segment 50, therefore it is useless to depress the button 75 since no current can flow from the battery to the relay winding 30.

The lighting circuit for the automobile includes the battery 25, ammeter 40, wire 41, wire 80, overload circuit interrupter 81, wire 82, switch contact 83, which is adapted to be connected with terminals 84, 85 and 86 by means of a switch element 87 mechanically connected to a lever 88 but insulated therefrom. Said member 87 is provided with detents 89, 90 and 91. In 80 the off position as shown in the diagram, detent 89 is engaged by spring 47. When the lever 88 is turned in a clockwise direction until the detent 90 is engaged by the spring 37 the switch contact will be connected with terminals 84 and 85 thereby completing a lighting circuit through the rear light and side lights through ground connections to the battery. When the lever 88 is turned still farther in a clockwise 90 direction until the detent 91 is engaged by the spring 47, the head lights will also be connected with the battery.

Suitable locking devices may be provided for locking the ignition switch lever 46 in 95 the off position when the car is left standing, thereby assisting in preventing theft of the car and preventing depletion of the storage battery by meddlers.

While the form of mechanism herein 100 shown and described constitutes a preferred form of embodiment of the invention, it is to be understood that other forms might be adopted, all coming within the scope of the claims which follow.

I claim—

1. In a controlling device for electrical ignition and starting systems, the combination with a contact connected with a current source; of a second contact connected 110 with an ignition system; a starting motor switch connected with said second contact; a third contact connected with another ignition system; and a movable switch member having spaced wide and narrow contact segments whereby in the off position of said movable member none of the contacts will be connected, whereby in one on position of said member all three of said contacts will be connected, and whereby in another on position of said member only the first two contacts will be connected.

2. In a controlling device for electrical ignition and starting systems, the combination with a rotatable switch shaft; of a contact connected with a current source; a second contact connected with an ignition system, said first and second contacts being in radial alignment with said shaft; a starting motor switch connected with said second 125 130

contact; a third contact connected with another ignition system; and a movable switch member mounted on said shaft and having spaced wide and narrow contact segments 5 whereby in the off position of said movable member none of the contacts will be connected, whereby in one on position of said member all three of said contacts will be connected, and whereby in another on

position of said member only the first two 10 contacts will be connected.

In testimony whereof I affix my signature.

WILLIAM H. MOONEY.
